OIL BURNER

Filed Sept. 8, 1924

2 Sheets-Sheet 2

UNITED STATES PATENT OFFICE.

THOMAS A. BIGGS, OF SIOUX CITY, IOWA.

OIL BURNER.

Application filed September 8, 1924. Serial No. 736,464.

My invention relates to oil burners of the general type in which an air flue directs downwardly a draft of air upon a bowl containing a porous refractory material, into 5 which the oil is fed, and involves a number of improvements upon the burner illustrated in my co-pending application serially numbered 672,678, filed November 3, 1923.

An object of my invention is to provide 10 in such a burner simplicity and durability of construction together with the novel features which will hereinafter be pointed out.

It is my object to provide means for agitating the porous refractory material within 15 the bowl of the burner in order to prevent the caking of the mass due to the forming of carbon in the interstices thereof.

Another object is to provide means for facilitating the dispersing of the oil from the 20 end of the oil feed pipe into the mass of refractory material. This object is preferably carried out by means of an apertured sleeve surrounding the pipe.

A further object is to provide means for 25 rotating the sleeve to prevent blocking of the space between the sleeve and the pipe.

A still further object is to provide a construction wherein the aforementioned sleeve is combined with an oil-spreading plate embedded 30 in the refractory mass near the top thereof, the sleeve and plate being retained in position by means of an overflow tube extending through and above the feed pipe and through the plate, and having a collar 35 adapted to engage the plate.

A further object is to provide means for mixing water vapor with the gas vapor in order to improve the combustion of the 40 burner.

A still further object is to provide an air flue having a downwardly-directed neck, which is adjustable in a horizontal plane to any position over the bowl.

Another object is to provide, in addition 45 to the downwardly-directed air flue, an air passage surrounding the bowl, whereby oxygen for combustion may be supplied on both sides of the ring of flame formed by the burner.

A further object is to provide novel means 50 for supporting the bowl within a casing,

between which and the bowl the outer air passage is formed.

With these and other objects in view, my invention consists in the construction, arrangement and combination of the various parts of my device, whereby the objects contemplated are attained, as hereinafter more fully set forth, pointed out in my claims and illustrated in the accompanying drawings, in which:

Fig. 1 is a perspective view of the burner with the sleeve rotating means in place.

Fig. 2 is a plan view of the burner base.

Fig. 3 is a plan view of the oil-spreading 65 plate.

Fig. 4 is a vertical longitudinal view through the burner, the sleeve rotating means being shown removed from engagement with the sleeve.

Fig. 5 is a horizontal transverse sectional view through the feed pipe and sleeve, taken on the line 5—5 of Fig. 4.

In the accompanying drawings I have used the reference character 10 to indicate 75 the cylindrical sides of the burner base. On one side thereof is formed an extruding semi-cylindrical sleeve, 11, in the upper edge of which, adjacent the junctures of the sleeve, 11, with the sides, 10, are the slots, 12. 80 The base is reinforced by the bottom flange, 13, and the ribs, 14, which at their upper ends, are beveled as at 15. (See Fig. 4.)

The burner bowl has the vertical cylindrical sides, 16, which, when the bowl is in 85 place, are spaced from the side of the casing so as to leave the air vent, 17. The lower portion of the bowl has the form of a truncated cone, as at 18, and the bottom, 19, is thickened to allow for a threaded opening 90 for the feed pipe, which will hereinafter be described.

The bowl at one side has the inwardly arched portion, 20, which, when registering with the portion, 11, forms a cylindrical air 95 passage and sleeve to receive the lower end of the air flue, which will hereinafter be described. The ears, 21, which continue the curve of the arch, 20, are adapted to be received in the slots, 12, for supporting one 100 side of the bowl and for positioning the bowl. The bowl is supported at its other

side by the upper beveled edges of the ribs, 14.

It will be seen that the bowl is thus supported in fixed spaced relation to the casing, 10, and yet is easily removable therefrom.

The air flue has the vertical tube divided by the flange, 22, into the upper and lower portions, 23^a and 23^b, respectively. The portion, 23^b, is received within the sleeve, 11, formed by the members, 11 and 20, and is slightly spaced therefrom as indicated at 24.

The casing, 10, is designed to be supported on the grates of a furnace, and ordinarily the grates will obstruct a portion of the opening in the bottom of the sleeve, 11. The space, 24, therefore allows air from other points within the casing to encircle the lower end, 23^b, of the air flue, and the slots, 25, allow such air to enter the flue. The flue rests upon the casing and bowl and is supported thereon by means of the flange, 22.

It will be seen that the flue may be rotated. At the upper end of the vertical portion of the flue is the upwardly arched housing, 26, which receives the horizontal portion, 27, of the flue. The discharge neck, 28, normally extends downwardly over the center of the bowl. The tube, 27, is slidably and rotatably adjustable in the housing, 26, and by rotating the vertical portion of the tube and sliding and rotating the horizontal portion, 27, the discharge mouth of the flue may be positioned at any point above the bowl in order to compensate for drafts within a furnace in which the burner is installed, which may tend to distort the flame of the burner. The opening, 30, in the tube, 27, provides communication with the vertical portion, 23^a, of the flue.

Oil is supplied to the burner through a feed pipe, 31, connected by means of a union, 32, with a short vertical section of piping, 33, which is threaded into the base, 19, of the bowl. The oil feed discharge pipe, 34, is threaded into the same opening and extends upwardly somewhat above the center of the bowl. Surrounding the pipe, 34, is a sleeve, 35, which is spaced therefrom. Surrounding the sleeve, 35, is a mass of porous refractory material such as gravel, 36.

As the oil is discharged from the upper end of the feed pipe, 34, it escapes into the mass of gravel, 36, through the longitudinal slot, 37, in the sleeve, 35. (See Fig. 5.) The sleeve, 35, protects the upper end of the tube, 34, from clogging with gravel, and allows the oil to spread over a considerable surface before encountering the gravel. By allowing the oil to escape from the relatively long aperture, 37, the danger of the discharge opening for the oil becoming clogged is minimized.

As explained in my co-pending applica-

tion heretofore referred to, the refractory material, 36, is heated by the flame from the burner and the heat is conducted therethrough to the bottom of the mass, the oil being vaporized near the bottom thereof and ascending upwardly in the form of a gas to be burned at the surface.

In order to correctly form the ring of flame, the deflecting plate, 38, described in my former application, is provided, being herein formed as an integral part of the sleeve, 35.

Through an opening in the center of the plate, 38, the oil overflow tube, 39, extends, and receives at its upper end a collar, 40, which engages the plate and secures the sleeve and plate in position. The lower end of the tube, 39, is threaded into the coupling, 32.

I find that the gravel frequently becomes caked with carbon forming in the interstices between the grains thereof, and in order to control this tendency I provide means for agitating the mass, which is as follows. In the side of the sleeve, 35, extending outwardly may be firmly embedded the agitating pins or fingers, 41. Similar fingers, 42, are supported by the plate, 38, and extend downwardly therefrom. By rotating the sleeve, the fingers will agitate the gravel sufficiently to keep it in a porous condition.

In order to rotate the sleeve I provide a crown ratchet ring, 43, formed on the upper surface of the plate and concentric therewith. The co-acting ratchet member, 44, has a downwardly-projecting stud or post, 45, adapted to enter the upper end of the tube, 39, for centering the member, 44, in position in engagement with the ring, 43. A handle, 46, may be provided to extend out through the door of the furnace in which the burner is installed, and by swinging the handle, 46, back and forth the sleeve, 45, may be completely rotated. When not in use, the driving member, 44, is removed through the mouth of the furnace.

In order to prevent the sleeve, 35, working to a position eccentric of the pipe, 34, wherein the slot, 37, would be closed by said pipe, I provide a vertical longitudinal rib, 47.

In addition the rib, 47, serves to prevent the formation of carbon on the exterior of the feed pipe, 34, by scraping the same when the sleeve is rotated.

I provide the tube, 48, which is threaded into the bowl near the bottom thereof, and which is adapted to be connected with a source of water supply in order to feed water into the bowl. The water will be converted to steam, and when used in the correct quantity aids in the combustion of the hydrocarbons.

Referring to the operation of my device, it will be seen that the flame will be formed

around the periphery of the plate, 38, and will be forced outwardly against the wall, 16, by the outwardly spreading blast of air from above. As the flame passes the upper edge of the wall, 16, it will contact with the current of air surrounding the bowl and issuing from the space, 17. This current of air helps to preserve the cylindrical shape of the flame, supplies an abundance of oxygen for the outer surface of the flame, and thus a perfect combustion may be obtained, the flame being surrounded on all sides by currents of air.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. In an oil burner, a bowl, a mass of porous refractory material therein, a plate embedded in the mass near the top thereof and spaced from the sides thereof, means for feeding oil into the mass below the plate, means for rotating the plate, and an agitating finger extending from the plate into the mass.

2. In an oil burner, a bowl, a mass of porous refractory material therein, a plate embedded in the mass and having an agitating finger extending into the mass, and means for rotating the plate.

3. In an oil burner, a bowl, an oil feed pipe extending into the bowl from the bottom thereof, a sleeve surrounding the feed pipe, a mass of porous refractory material surrounding the sleeve, an agitating finger fixed to the sleeve and extending into the mass, and means for rotating the sleeve.

4. In an oil burner, a bowl, an oil feed pipe extending thereinto from the bottom thereof, a sleeve surrounding the feed pipe and closed at its top, said sleeve having an oil discharge slot in its side, means for rotating the sleeve, and a mass of refractory porous material surrounding the sleeve.

5. In an oil burner, a bowl, a mass of porous refractory material therein, a circular imperforate plate embedded in the mass and spaced slightly from the side of the bowl on all sides and having an agitating finger extending into the mass, said plate being rotatable.

6. In an oil burner, a bowl, an oil feed pipe extending into the bowl from the bottom thereof, a sleeve surrounding the feed pipe, a mass of porous refractory material surrounding the sleeve, an agitating finger fixed to the sleeve and extending into the mass, said sleeve being rotatable.

7. In an oil burner, a bowl, an oil feed pipe extending thereinto from the bottom

thereof, a sleeve surrounding the feed pipe and having an oil discharge slot in its side, a plate on the sleeve at the upper end thereof, said plate being spaced from the sides of the bowl, a mass of porous refractory material surrounding the sleeve and embedding the plate, agitating means fixed to the sleeve and extending into the refractory mass, and means for rotating the sleeve and plate.

8. In an oil burner, a bowl, an oil feed pipe extending thereinto from the bottom thereof, a sleeve surrounding the feed pipe and having an oil discharge slot in its side, a plate on the sleeve at the upper end thereof, said plate being spaced from the sides of the bowl, a mass of porous refractory material surrounding the sleeve and embedding the plate, agitating means fixed to the sleeve and extending into the refractory mass, and means for rotating the sleeve and plate, said means comprising a crown ratchet ring on the plate, and a crown ratchet driving member detachably engageable with the said ring.

9. In an oil burner, a bowl, a mass of porous refractory material therein, a plate embedded in said mass, an agitating member on the plate extending into the mass, a crown ratchet ring on the plate, the plate having an opening centered with relation to said ring, and a crown ratchet driving member removably engageable with the said ring, said driving member having a centering post receivable in said opening.

10. In an oil burner, a bowl, an oil feed pipe extending thereinto from the bottom thereof, a longitudinally apertured sleeve surrounding said pipe, a longitudinal rib on the interior of said sleeve protruding inwardly toward the feed pipe, and means for rotating the sleeve.

11. In an oil burner, a bowl, an oil feed pipe extending thereinto from the bottom thereof, a longitudinally apertured sleeve surrounding said pipe, a scraper on the inner surface of the sleeve adjacent an edge of the aperture thereof, the sleeve being rotatable.

12. In an oil burner, a casing, a bowl supported therein and spaced therefrom so as to provide an air passage surrounding the bowl, refractory material in the bowl substantially filling the same, an imperforate plate embedded in the refractory material near the surface thereof, means for introducing oil into the bowl below the plate, and an air flue supported at one side of the casing and communicating therewith, said flue having a downwardly arched discharge neck centered over the bowl.

13. In an oil burner, a casing having at one side an extruding semi-cylindrical sleeve, said sleeve having at its upper edge near the junctures of the sleeve with the casing a pair of slots, a bowl having at one

side a pair of ears adapted to be received in said slots, means in the casing positioned diametrically opposite the sleeve for supporting and spacing the bowl concentric with the casing, said bowl being of sufficiently smaller diameter than the casing to provide an air passage between the bowl and the casing, and an air flue having its lower end received within the semi-cylindrical sleeve and its upper end directed downwardly over the bowl.

14. In an oil burner, a bowl, a vertical air

flue rotatably supported relative to said bowl, a horizontal cylindrical housing on the upper end of said vertical flue, a flue section slidably and rotatably mounted in said cylindrical housing, and having a downwardly directed discharge neck adapted to be positioned over the bowl.

15
Signed at Sioux City, in the county of Woodbury and State of Iowa, this 3rd day of September, 1924.

THOMAS A. BIGGS.
